CONTROL FOR HYDRAULIC GREASE
DISPENSERS

Anthony Bizzarri, New York, N. Y.

Application May 12, 1933, Serial No. 670,655

10 Claims. (Cl. 221—47.1)

My present invention relates to grease-dispensing devices and more particularly to controls for automatically regulating the volume of flow of lubricating substances such as heavy 5 grease, to the place where it is to be used, depending upon the resistance with which such flow meets at the place receptive thereof. One of the objects of my present invention is to provide devices of the general character specified, which are 10 simple in construction, easy and economical to fabricate and assemble, and which are admirably adapted to perform the functions heretofore mentioned.

Other objects and advantages of the present 15 invention will in part be pointed out hereinafter and will in part be obvious to one skilled in the art to which the present invention relates.

In the accompanying specification I shall describe and in the annexed drawing show an illustrative embodiment of a grease-dispensing device provided with control means made in accordance with the present invention, it is however, to be clearly understood that I do not wish to be limited to the exact details of the aforesaid 25 illustrative embodiment of the present invention herein shown and described for purposes of illustration only.

In the accompanying drawing, Fig. 1 is a longitudinal sectional view taken substantially 30 through the center of a grease-dispensing device provided with controls made in accordance with the present invention;

Fig. 2 is a transverse view taken along lines 2—2 of Fig. 1; and

Fig. 3 is a fragmentary front elevational view of the same, partially broken away to show the interior construction.

Referring now more in detail to the aforesaid 40 illustrative embodiment of the present invention and with particular reference to the drawing illustrating the same, the numeral 5 generally designates a rectangular carriage supported at its four corners upon casters 6, the upper surface of the carriage 5 being provided with an annular 45 upstanding flange 7 receptive of a double container 8. The double container 8 consists of an outer bottom wall 9 provided with a central opening closed by a cap 10. Rising from the periphery of the outer bottom wall 9 is a cylindrical outer side wall 11 connected at the top thereof with a sloping annular upper wall 12. The latter has 50 integrally formed therewith a cylindrical inner side wall 13 extending within the outer side wall 11 and which is closed at its lower end by an inner bottom wall 14. The inner bottom wall 14

is provided with a central opening 15 surrounding which, on the outer surface of the wall 14, is a valve seat 16 adapted to cooperate with a valve 17, the purpose of which will later be described. The valve 17 is carried on the lower threaded 60 end of a rod 18 extending upwardly through the center of the double container 8, and is provided at its upper end with a handle 19 adapted to retain in place a cover 20, the handle maintaining the cover in close contact with the point of connection 21 between the upper wall 12 and the inner wall 13. Slidable on the rod 18 and closely fitting the inner wall 13 is a follower 22, the undersurface of which has fixed thereto a chain 23, the lower end of which is secured to a by-pass 70 valve 24 controlling a passage 25 communicating between an oil reservoir 26 formed between the outer walls and the inner walls of the double container 8 and the oil-receiving lower portion 27 of a grease-reservoir 28 formed within the 75 inner wall 13 and above the follower 22.

Fixed to the undersurface of the carriage 5 is an electric motor 29, the shaft 30 of which is connected by a coupling 31 with a stub-shaft 32 journaled in a bearing 33 formed in a pump 80 housing 34 carried by the carriage. The end of the stub-shaft 32 within the housing 34 has secured thereto a ball-bearing eccentric 35 adapted to successively and progressively operate a plurality of radially disposed pumps carried in 85 the housing 34, and being shown in the drawing, as 3 oil pumps 36 and 3 grease pumps 37. Inasmuch as all of the oil pumps are similar, only one need here be described. Each of the pumps 36 consist of a cylinder 36' within which there is adapted to reciprocate a spring-pressed piston 36''. Inasmuch as all of the grease pumps 37 are similar, only one of the same need be described. Each of the grease pumps 37 includes a cylinder 37' within which there is adapted to 95 reciprocate a spring-pressed piston 37''.

The pump housing 34 is provided with an annular passage 38 from which branch off 3 oil pump inlets 39. The housing is further provided with 3 oil pump outlets 40 controlled by 100 valves 41, the outlets 40 in turn communicating with an annular passage 42 connecting with a pipe 43 extending upwardly through the bottom wall 9 of the oil reservoir 26, passing through the latter and extending through the bottom wall 14 of the lower portion 27 of the grease-reservoir 28. The annular passage 38 also communicates with an inlet passage 44 communicating with a passage 45 formed in a casting 46, the last named 105 110

passage connecting with a pipe 47 extending within the oil reservoir 26.

The pump housing 34 is also provided with another annular passage 48 from which branch off 3 grease pump inlets 49. The housing is further provided with 3 grease pump outlets 50 controlled by valves 51, the outlets 40 communicating with a final annular passage 52. The annular passage 52 communicates with an outlet port 53 and the annular passage 42 communicates with an inlet passage 54 which in turn is connected with another passage 55 formed in the casting 46, the latter passage communicating with a pipe 56 extending upwardly through the oil reservoir 26 and opening into the grease-reservoir 28.

The outlet port 53 communicates with a hose 57 to which there is connected an operating member generally designated by reference character 58. The operating member 58 consists of a passage 59 in communication with the hose 57, an outlet passage 60 and an intermediate passage 61 communicating between the passages 59 and 60 and in which there is a spring-pressed ball valve 62 controlling such communication. The ball valve 62 bears against a pin 63 which in turn is operated by a pivoted handle 64. The outlet passage 60 communicates with an additional hose 65 at the end of which there is provided a bayonet coupling 66 of conventional construction.

I have thus described a grease-dispensing device with which the control means constituting the present invention may be used with admirable success, it being understood of course that any other grease-dispensing device can be used in connection with the control of the present invention, and this will be obvious from the description of the control means itself which is as follows:

The gist of the present invention is a means for controlling the volume of oil delivered from the oil-reservoir 26, by way of the oil pumps 36 to the oil-receiving lower portion 27 of the grease reservoir 28 and the volume of grease delivered from the grease reservoir 28 to the hose 57 by way of the grease pumps 37, such means being automatic in operation and depending upon the resistance with which the grease meets at the outlet, or coupling 66.

Such control means consists of a pair of sliding valves 44' and 54' to which are secured pins 67, the diameters of which are less than the diameters of the passages 44 and 54. The outer surface of the valve 44' has fixed thereto a pin 68 extending within the port 53 so as to be acted upon, as will later be described, by the pressure of the grease within the port 53. The inner pin 67 has fixed thereto a piston 69 against which bears a spring 70 the tension of which is adjustable by means of a set screw 71, the spring 70 and set screw 71 being housed by a cylinder 72.

This completes the description of the aforesaid illustrative embodiment of the control means for grease-dispensing devices of the present invention. It is believed that the mode of operation and use is apparent from the foregoing description, but for the sake of clarity, the same may be briefly summarized as follows:

To begin with the reservoir 26 is filled with a relatively light oil, the follower 22 is at the bottom of the grease reservoir 28 and the latter is filled with a relatively heavy grease. Through the motor 29 the eccentric 35 is operated which in turn acts upon the plungers 36'' and 37'' respectively of the oil and grease pumps 36 and

37. Oil from the reservoir 26 is drawn through the pipe 47 passages 45 and 44 to the annular passage 38 from where it is distributed through the inlets 39 to the pumps 36. From the pumps 36 the oil is forced through the outlet passages 40 past the valves 41 and into the annular passage 42. From this point the oil passes by way of the pipe 43 into the lower portion 27 of the grease container 28, beneath the follower 22. As the hydraulic pressure is built up beneath the follower 22 the latter is forced upwardly thus forcing the grease above the same in the reservoir 28 out of the reservoir 28 and through the pipe 56 and passages 55 and 54 to the annular passage 42 from where it is distributed by means of the inlets 49 to the grease pumps 37. From the grease pumps the grease passes through the outlets 50 past the valves 51 and into the annular passage 52. From this point the grease enters the port 53 and passes out of the housing 34 by way of the hose 57. The operator when desiring to lubricate some piece of machinery with heavy grease, secures the bayonet coupling 66 in place upon the device to be lubricated and depresses the handle 64. This opens the valve 62 and permits the grease to flow from the hose 57 through the passages 59, 61 and 60 to the additional hose 65 from where it is conveyed to the device to be lubricated through the coupling 66.

As the resistance met with by the grease being fed to the device to be lubricated increases, as when the device to be lubricated is approaching the point where it needs no further lubrication, a back pressure is built up in the port 53. This pressure acts upon the pin 68 to cause the valves 44' and 54' to slide longitudinally so as to effect a closing of the inlet passages heretofore described, with the oil and grease pumps 36 and 37. The result of the gradual closing off these passages is to reduce the volume of the oil delivered from the reservoir 26 to the lower portion 27 of the grease reservoir 28, beneath the follower 22 and the volume of the grease delivered from the reservoir 28 to the place where it is to be used for lubrication. The greater the resistance met with at the coupling 26 the greater the extent of closing of the sliding valves 44' and 54' so that eventually, even though the handle 64 is still depressed and the valve 62 open, and the motor 29 continues to operate the pumps 36 and 37, no additional grease will be delivered through the coupling 66. At that time the operator will release the handle 64 thus closing the valve 62 and maintaining the slide valves 44 and 54 under pressure, effectively keeping the passages 44 and 54 closed. As soon as the coupling 66 is attached to another device to be lubricated and the handle 64 depressed to open the valve 62 the pressure in the system will be reduced so that the spring 70 can return the slide valves 44' and 54' to their open positions permitting a continuation of the flow of oil and grease. It will be obvious that the pressure at which the slide valves 44' and 54' will operate may be regulated by the set screw 71, the greater the tension of the spring 70 the more resistance being necessary at the coupling 66 to effect a closing of the valves 44' and 54'.

When the follower 22 reaches a predetermined height, the chain 23 will be pulled taut and the by-pass valve 24 will open to permit the access oil in the lower portion 27 of the grease reservoir to pass out of the same and into the oil reservoir 26 by way of the passage 25. After the grease has been entirely ejected from the reservoir 28 and the follower 22 is at the top of

the grease reservoir and the entire grease reservoir beneath such follower is filled with oil, the handle 19 may be manipulated to remove the cover and open the valve 17 to permit the oil within the grease reservoir to pass out of the same and into the oil reservoir 26.

This completes the description of the mode of operation and use of the aforesaid illustrative embodiment of the present invention, and it will be apparent from all of the foregoing that the devices of the present invention are simple in construction, easy and economical to fabricate and assemble, and are admirably adapted to perform their intended function. Other 15 superiorities and advantages of the devices of the present invention will be obvious to those skilled in the art to which the present invention relates.

What I claim as my invention is:

20 1. In combination with a grease-dispensing apparatus consisting of a lubricant reservoir, a fluid reservoir, pumping means to convey the contents of the lubricant reservoir to a device to be lubricated and pumping means to convey the contents of the fluid reservoir to the lubricant reservoir to force the contents of the latter to the first mentioned pumping means, a volume-controlling device, comprising, means, operable by the varying resistance offered to the feeding 25 of the lubricant, to control the communications between the lubricant and fluid reservoirs and both of the pumping means.

2. In combination with a grease-dispensing apparatus consisting of a lubricant reservoir, a fluid reservoir, pumping means to convey the contents of the lubricant reservoir to a device to be lubricated and pumping means to convey the contents of the fluid reservoir to the lubricant reservoir to force the contents of the latter to the first mentioned pumping means, a volume-controlling device, comprising, means, operable by the varying resistance offered to the feeding of the lubricant, to open and close the communications between the lubricant and fluid reservoirs 40 and both of the pumping means.

3. In combination with a grease-dispensing apparatus consisting of a lubricant reservoir, a fluid reservoir, pumping means to convey the contents of the lubricant reservoir to a device to be lubricated and pumping means to convey the contents of the fluid reservoir to the lubricant reservoir to force the contents of the latter to the first mentioned pumping means, a volume-controlling device, comprising, means, operable by the varying resistance offered to the feeding of the lubricant, to control the communications between the lubricant and fluid reservoirs and both of the pumping means, said means including a duplex valve.

4. In combination with a grease-dispensing apparatus consisting of a lubricant reservoir, a fluid reservoir, pumping means to convey the contents of the lubricant reservoir to a device to be lubricated and pumping means to convey the contents of the fluid reservoir to the lubricant reservoir to force the contents of the latter to the first mentioned pumping means, a volume-controlling device, comprising, means, operable by the varying resistance offered to the feeding of the lubricant, to open and close the communications between the lubricant and fluid reservoirs and both of the pumping means, said means including a duplex valve.

5. In combination with a grease-dispensing apparatus consisting of a lubricant reservoir, a fluid

reservoir, pumping means to convey the contents of the lubricant reservoir to a device to be lubricated and pumping means to convey the contents of the fluid reservoir to the lubricant reservoir to force the contents of the latter to the first mentioned pumping means, a volume-controlling device, comprising, means, operable by the varying resistance offered to the feeding of the lubricant, to control the communications between the lubricant and fluid reservoirs and both of the pumping means, said means including a spring-pressed duplex valve.

6. In combination with a grease-dispensing apparatus consisting of a lubricant reservoir, a fluid reservoir, pumping means to convey the contents of the lubricant reservoir to a device to be lubricated and pumping means to convey the contents of the fluid reservoir to the lubricant reservoir to force the contents of the latter to the first mentioned pumping means, a volume-controlling device, comprising, means, operable by the varying resistance offered to the feeding of the lubricant, to open and close the communications between the lubricant and fluid reservoirs and both of the pumping means, said means including a spring-pressed duplex valve.

7. In combination with a grease-dispensing apparatus consisting of a lubricant reservoir, a fluid reservoir, pumping means to convey the contents of the lubricant reservoir to a device to be lubricated and pumping means to convey the contents of the fluid reservoir to the lubricant reservoir to force the contents of the latter to the first mentioned pumping means, a volume-controlling device, comprising, means, operable by the varying resistance offered to the feeding of the lubricant, to control the communications between the lubricant and fluid reservoirs and both of the pumping means, said means including a duplex valve, and means to adjust the degree of resistance at which said valve will operate.

8. In combination with a grease-dispensing apparatus consisting of a lubricant reservoir, a fluid reservoir, pumping means to convey the contents of the lubricant reservoir to a device to be lubricated and pumping means to convey the contents of the fluid reservoir to the lubricant reservoir to force the contents of the latter to the first mentioned pumping means, a volume-controlling device, comprising, means, operable by the varying resistance offered to the feeding of the lubricant, to open and close the communications between the lubricant and fluid reservoirs and both of the pumping means, said means including a duplex valve, and means to adjust the degree of resistance at which said valve will operate.

9. In combination with a grease-dispensing apparatus consisting of a lubricant reservoir, a fluid reservoir, pumping means to convey the contents of the lubricant reservoir to a device to be lubricated and pumping means to convey the contents of the fluid reservoir to the lubricant reservoir to force the contents of the latter to the first mentioned pumping means, a volume-controlling device, comprising, means, operable by the varying resistance offered to the feeding of the lubricant, to control the communications between the lubricant and fluid reservoirs and both of the pumping means, said means including a spring-pressed duplex valve, and means to adjust the degree of resistance at which said valve will operate.

10. In combination with a grease-dispensing apparatus consisting of a lubricant reservoir, a fluid

fluid reservoir, pumping means to convey the contents of the lubricant reservoir to a device to be lubricated and pumping means to convey the contents of the fluid reservoir to the lubricant reservoir to force the contents of the latter to the first mentioned pumping means, a volume-controlling device, comprising, means, operable by the varying resistance offered to the feeding of
